United States Patent Office

Des. 218,041

Patented July 14, 1970

218,041

COMPUTER KEYBOARD INPUT CONSOLE

Jeremy Soley Connolly, New York, N.Y., and Donald Louis Smith, Maywood, N.J., assignors to Realtronics, Inc., a corporation of New Jersey

Filed Apr. 24, 1969, Ser. No. 16,889

Term of patent 3½ years

Int. Cl. D14—02

U.S. Cl. D26—5

FIG.1.

FIG.2.

FIG.3.

FIG.4.

FIG. 1 is a perspective view of our computer keyboard input console showing our new design thereof;

FIGS. 2, 3 and 4, are top plan, side and front elevational views, respectively, thereof.

We claim:

The ornamental design for a computer keyboard input console, as shown.
